2 Claims. (Cl. 68—198)

1

This invention relates to yarn package supports and more particularly to a device adapted to support a yarn package, such as a cake of regenerated cellulose, during liquid treatment wherein the processing liquid is forced through the winding under pressure.

An object is to provide a device of the above type which eliminates defects of previous devices such as forming creases in the windings and reduces the time required for the treatment.

Another object is to provide a device of the above type having novel and improved characteristics.

Various other objects and advantages will be apparent as the nature of the invention is more fully disclosed.

The present invention provides for the treatment of unsupported yarn windings, in particular of untwisted rayon and permits systematic treatment of large unsupported yarn windings. It is characterized in that perforated expanding cylinders of a material not attacked by the processing liquids or by sulfur compounds are used to support otherwise unsupported yarn windings, with or without free axial expansion, which are flushed with processing liquids forced from the inside out, the flow being permitted to emerge both from the outer surface of the cylinder and on the two faces of the winding, its pressure effecting the axial expansion of the windings. The perforated expanding cylinder is pressed against the inside of the yarn winding during treatment, by the pressurized flow. Uniform pressure distribution of liquid is maintained over the entire surface of the cylinder and the amount of waste processing liquid is reduced to a minimum.

In one embodiment a support carries a perforated expanding cylinder which is in sealed connection with the support during treatment, the outside of such cylinder supporting the yarn winding to be treated and the inside being connected to a pressure line to supply the processing liquid.

The support may advantageously serve also for distribution of the liquor, and is accordingly perforated. In the interior of the perforated cylinder there is a perforated liner to reduce waste of liquor, resting on a base plate and surmounted by a washer, connected in turn by interchangeable spacer bushings with a conveniently attachable top plate. The latter represents the uppermost outside limit of the perforated cylinder, and at the same time the upper facial limitation of the yarn winding.

Greater or lesser vertical height of the bushings serves to restrict axial expansion of the windings to various extents, so that for each type of winding, the most economical balance between consumption of liquor and processing effect can be obtained. The type of winding, dimensions of perforations and amount of liquid pressure afford further possibilities of varying this equilibrium. The cylinder may comprise a cylindrically curved perforated sheet of flexible stainless steel with side edges overlapping and adapted to expand radially under the pressure of the processing liquor, the overlapping edges being forced tightly together as this expansion is externally limited by the windings. Annular washers of inside diameter such as to remain greater than the inside diameter of the windings during treatment at maximum pressure have their perforated faces covering the yarn windings to be treated. The end washers are fixed to the supporting column and to the liner during treatment by means of spacers and a quick-locking device, while the center washer is free to slide axially on the elastic cylinder to permit axial expansion of the lower winding during treatment. The frontal seal between support, liner and perforated cylinder may advantageously be secured by means of rubber or other deformable packing, pressed into suitable recesses by the pressure of the processing liquids from the inside against the perforated cylinder and the sides of the recesses in the support and liner. To prolong the life of these packings, helical steel springs may advantageously be vulcanized there-in.

Another embodiment confines itself to sealing the perforated expanding cylinder to the end washers, the latter being fitted on the inside with cemented gaskets of elastic material, e. g. rubber, against which the cylinders are expanded by the pressure of the processing liquids.

By suitable design of the perforations and/or shape of the liner and/or liquid supply line, a uniform distribution of liquid pressure along the surface of the jacket can be obtained. In addition, the perforations are of such size as to apply the maximum liquid pressure to the gaskets, while the jacket surfaces are under lower pressure, to ensure complete outward seal of the support.

Of course, all parts of the equipment described are of material not attacked by any of the liquids used for the treatment of unsupported yarn windings.

A specific embodiment of a device for practic-

ing the present process will be explained in terms of the accompanying drawings wherein:

Fig. 1 is a vertical section through a processing column embodying the invention; and

Fig. 2 is a diagrammatic view of equipment for processing a bank of unsupported yarn windings with liquids under pressure.

The processing column shown in Fig. 1 comprises a central pressure tube 1, provided with holes 2 and rigidly connected to base plate 3 and pedestal 4. A liner 5, provided with a large number of perforations of smaller diameter 6 and a certain number of perforations of larger diameter 7 communicating with recesses 8, is disposed around the tube 1. Elastic packing rings 9, such as rubber, fit into the recesses 8. A washer 10 is attached to a pin 20 which is carried in the end of tube 1 and serves to hold the liner 5 and also the upper packing ring 9 in position. A cylinder 11 of flexible stainless steel having perforations 11a is disposed around the liner 5 and sealed by the packing ring 9. The cylinder 11 is split as indicated at 11b so as to be expandable. A top plate 13 is attached with wing nut 12 to pin 20 with spacer 19 and lock nut 12a. The top plate 13 is formed with a depending skirt 21 having a flared flange 22, with perforations 22a, adjacent to the top of yarn winding 16. A lower sleeve 23 having a flared flange 15, with perforations 15a, rests freely on base 3.

For treatment, unsupported yarn windings 16 with or without protective covering of fabric are mounted from above on perforated cylinder 11. The bottom winding rests on flange 15. A separate sleeve 24 having flanges 14 separates the windings. The top winding 16 is surmounted by flange 22 of the top plate 13 and is fixed in place with wing nut 12. It is essential that the flange 22 and the top winding 16 have a certain clearance 17 between them.

If the processing liquid under pressure is introduced through the central tube 1 into the processing column, then, with some slight pressure drop, the liquid will flow into the recesses 8 and press packing rings 9 against perforated cylinder 11, thereby sealing the cylindrical spaces 18 between liner 5, perforated cylinder 11, and yarn windings 16 at both ends. At the same time the processing liquid flows, with somewhat greater pressure drop, through the smaller perforations 6; enters the aforesaid cylindrical spaces 18, thereby pressing the split cylinder 11 against the windings, penetrates through the perforated cylinder 11 into the yarn windings 16, and emerges on the outside of the windings, then either being drained off or being recirculated as in Fig. 2. As the liquid penetrates into windings 16, the latter tend to expand axially. They can so expand axially into the available free space 17, being freely movable from below, together with the center spacer 24 upon the perforated cylinder.

The equipment shown in Fig. 2 consists of processing columns 31 carried in trough 32 with a hood 33 provided for removal of noxious gases or for recovery of vaporized materials through a duct 34. The liquid emerging from windings 16 is carried to a receiving tank 26 by a return line 25, the former likewise serving for separation of incidental impurities. A pump 27 is at-

tached to this tank 26, and forces the processing liquid, after concentration, if necessary, through the pressure line 28, through suitable pressure filters if needed, and back into the processing columns 31.

It is evident that the split cylinders 11 is forced against the inner periphery of the windings 16 by the pressure of the treating liquid from the pipe 1 and is sealed by packing rings 8 so that all of the liquid is forced to pass through the windings 16. The perforated flanges 15, 14 and 22 allow liquid to flow out of the ends of the windings. Hence all parts thereof are equally and uniformly treated. The cylinder 11 conforms to any radial expansion of the windings and the space 17 allows a limited axial expansion under the influence of the treating liquid.

What is claimed is:

1. An apparatus for supporting yarn packages for processing, comprising a fixed cylindrical support having an axial bore and radial passages communicating therewith through which processing liquid is adapted to flow, a base plate projecting radially beyond said support, an expandable split perforated cylinder disposed on said base plate around said support and spaced therefrom to provide an annular passage therebetween and adapted to carry a series of windings arranged in a column around said split cylinder for processing, a bottom ring disposed on said base plate around said split cylinder and having a flange shaped to support the bottom of the lower winding of said column, a spacing ring sliding on said split cylinder having flanges shaped to space and support successive windings, a fixed top ring around said split cylinder having a flange initially spaced from the top of the upper winding of the column, elastic packing rings carried by said support in alignment with said bottom, top and spacing ring and sealing said support to said split cylinder to close said annular passage at the top and bottom of each winding, said split cylinder and said packing rings being adapted to be expanded radially under the pressure of the processing liquid from said axial bore to engage the inner periphery of said windings, said spacing rings sliding on said split cylinder to allow said windings to swell and elongate axially until the upper winding is brought into sealing contact with the flange of said fixed top ring, whereby the processing liquid from said support is confined to the windings.
2. An apparatus, as set forth in claim 1, in which said split cylinder is formed of a stainless steel sheet with overlapping longitudinal edges, which are adapted to be sealed together by the pressure of the processing liquid.
